COMBINED HOLDER AND EXTINGUISHER FOR A CIGARETTE

Samuel Lustbader, 2815 W. 30th St.,
Brooklyn, N.Y. 11224

Filed Oct. 12, 1966, Ser. No. 4,251

Term of patent 14 years

(Cl. D85—2)

FIG. 1.

FIG. 3.

FIG. 2.

FIG. 4.

FIG. 1 is a perspective of a combined holder and extinguisher for a cigarette showing my new design, with a cigarette shown in broken lines for purposes of illustration only;

FIG. 2 is a side elevational view thereof with the base member omitted for convenience of illustration;

FIG. 3 is a top plan view of FIG. 2; and

FIG. 4 is a bottom plan view of FIG. 2.

The essential features of my design are shown in the full line portions thereof.

I claim:

The ornamental design for a combined holder and extinguisher for a cigarette, as shown and described.
